DESIGN FOR A PORTABLE BAR

Wendell P. Hopkins, Beverly, Mass.

Application June 8, 1945, Serial No. 119,956

Term of patent 14 years

(CL. D33—19)

To all whom it may concern:

Be it known that I, Wendell P. Hopkins, a citizen of the United States, residing at Beverly, in the county of Essex and Commonwealth of Massachusetts, have invented a new, original, and ornamental Design for a Portable Bar, of which the following is a specification, reference being had to the accompanying drawing forming a part thereof, in which:

Fig. 1 is a plan view of a portable bar showing my new design.

Fig. 2 is a view of the same in front elevation. Fig. 3 is a view in perspective of the bar. The back and both sides of the bar present plain surfaces.

I claim:

The ornamental design for a portable bar, as shown and described.

WENDELL P. HOPKINS.
